UNITED STATES PATENT OFFICE.

JOSEPH E. CURRY, OF LAWRENCE, KANSAS.

WIND-GAGE FOR THRASHING AND CLEANING MACHINES.

SPECIFICATION forming part of Letters Patent No. 276,781, dated May 1, 1883.

Application filed December 21, 1882. (No model.)

To all whom it may concern:

Be it known that I, JOSEPH E. CURRY, of Lawrence, in the county of Douglas and State of Kansas, have invented a new and Improved 5 Wind-Gage for Thrashing and Cleaning Machines, of which the following is a full, clear, and exact description.

My invention consists of a ball-governor attachment to the wind-boards of the fan-blower of cleaning attachments to thrashing-machines, the object being to provide automatic regulating apparatus, essentially as hereinafter described and claimed, for the fan-blower, in order to prevent the waste of good grain, caused 15 by the force of the blast being too great whenever the speed of the machine increases too much by reason of irregularity in feeding and other causes, by which the grain is blown over or back into the elevator, and to admit more 20 wind to clean the grain when the speed of the machine decreases.

Reference is to be had to the accompanying drawings, forming part of this specification, in which similar letters of reference indicate corresponding parts in both the figures.

Figure 1 is a side elevation of the governor and section of the supporting-base containing the wind boards or valve of the fan-blower, and Fig. 2 is a transverse section of part of 30 Fig. 1.

The side pieces, *a*, and cross-pieces *b*, forming the supporting-base for the spindle *c* of the ball-governor, are intended to represent the part of the fan-blower attachment of a 35 cleaning apparatus for thrashing-machines,

through which the wind-blasts of the blower *r* pass, and which I propose to regulate by the wind boards or valves *d*, and a governor connected to them by levers *e* and chains *f*, said governor consisting of the usual centrifugal balls, *g*, arms *h*, connecting-rods *i*, and sleeves *k* and *l*, mounted on the spindle *c* and geared with the machine by the bevel-wheels *m*, belt *n*, and a pulley, *o*, or by any other approved means.

The contrivance can be readily applied to any machine.

The importance of such an attachment will be appreciated by all who are familiar with the many causes of irregularity in the speed of thrashing-machines and the great waste of grain caused thereby.

Having thus fully described my invention, I claim as new and desire to secure by Letters Patent—

The blast-regulating attachment for fan-blowers of thrashers, which consists essentially of the governor *g h i k e l*, pivoted levers *e*, boards *b*, valves *d*, pivoted or hung to operate in the wind-passages of the blower, said valves being connected directly to the said levers, and the latter being connected directly to the sliding sleeve of the governor, beveled-gear wheels *m*, pulley *o*, and belt *n*, adapted to drive the blower, essentially as shown and described.

JOSEPH E. CURRY.
